UNITED STATES PATENT OFFICE.

CARL ANDREAS ADAM, OF HAMBURG, GERMANY.

MEANS FOR PRODUCING PRINTING PLATES SPECIALLY FOR POSTER PRINTING.

Application filed December 15, 1926, Serial No. 155,066, and in Germany January 6, 1926.

The present invention relates to means for producing lines for printing which are especially used for poster-printing, the printing plates or types and the block which holds the types being fitted with teeth and counter teeth or other means adapted to engage with one another, and designed to secure against displacement in lateral directions and without the aid of justifiers the types or printing plates mounted on the block spaced the one 10 from the other.

The teeth on the plate-block made of one or of several parts and on the types or printing plates are formed, for instance, by transversely or longitudinally or transversely and longitudinally extending grooves or ribs. The teeth on the block might be produced by toothed bars enclosed between elements of the block which are either of equal size or of different size and have no teeth. The connection between the printing plates or types and the block, made in one or several pieces, is effected by convenient means, for instance by clamping-bars or by facet-bars.

Several embodiments of the invention are illustrated, by way of example, on the accompanying drawing in which:—

Fig. 1 shows in top plan view,

Fig. 2 in front elevation and

Fig. 3 is side elevation a plate-block and some printing plates or types fixed on the same.

Figs. 4 and 5 show each in front elevation a portion of a block with printing plate having teeth of other shape than those shown in Fig. 2.

Figs. 6 and 7 show each in side elevation a portion of a block and printing plate or type with clamping bar or facet-bar of other shape than those shown in Fig. 1.

Fig. 8 shows in perspective view a form of construction in which the counter teeth are formed by a bar held between two equal parts of a block.

In the drawing three printing plates or types a , a^1 , a^2 are shown, by way of example, which together form the word "Ale". They have grooves or ribs e in or on the lower surface. Similar grooves or ribs f are arranged on the block b . The teeth and coun-

ter teeth secure the printing plates or types a , a^1 , a^2 on the block b against mutual displacement. The block and the printing plates or types are of equal breadth and arranged at the front end and at the rear end for the reception of clamping bars or facet-bars d , the lower longitudinal edges of the block b having with this object in view bevelled or broken edges i (Figs. 3, 6, 7 and 8), and the vertical long sides of the printing plates or types a , a^1 , a^2 have also bevelled or broken edges c (Fig. 7). Longitudinal grooves c^2 (Figs. 3, 6 and 8) are cut into the same, so that by the correspondingly shaped facet bars d , d^1 , d^2 the printing plates or types a are securely held on the block b in the printing frame known per se.

The teeth and counter teeth of the printing plates or types a and of the block b might be of the shape shown in Figs. 4 and 5. The teeth are designated in Fig. 4 by e^1 and f^1 and those in Fig. 5 are designated by e^2 and f^2 .

The clamping or facet bars may be in cross section of the shapes shown in Fig. 2, in Figs. 6 and 8 or in Fig. 7.

As can be seen in Fig. 8 of the drawing the block may be composed of two equal longitudinal parts b and b^1 so that between the two parts a bar b^2 can be accommodated which has teeth f^3 in its upper edge and designed to engage with longitudinal grooves e^3 in the lower surface of the printing plates or types a .

The block may be composed, as shown in Fig. 2 of the drawing, of transverse bars which have each teeth in the top edge. Bars b^3 having one row of teeth, bars b^4 having two rows of teeth, bars b^5 having three rows of teeth and bars b^6 having still more rows of teeth may be used. The plate-block might further, as shown in Fig. 3 of the drawing, be subdivided in transverse direction so that it is composed for instance of three transverse parts b^7 , b^8 , b^9 .

I claim:—

1. In combination, a printing impression member formed on its rear surface with a narrow row of teeth extending transverse the member, and a block made up of a series of independent sections, each formed with a row 100

of teeth corresponding to that on the impression member, the row of teeth on each of the several sections aligning when the sections are assembled in block form.

5 2. In combination, a printing impression member formed with a row of ribs extending transverse the printing line of the member, a block having a corresponding row of ribs extending longitudinally thereof, whereby

the impression member may be interlocked with the block at any point throughout its length, and means interfitting with the edges of the member and block to hold the member against movement on the block in a direction at right angles to the holding ribs. 15

In testimony whereof I affix my signature.

CARL ANDREAS ADAM.
